US00D948353S

(12) **United States Design Patent** (10) **Patent No.:** **US D948,353 S**
Tinius (45) **Date of Patent:** **** Apr. 12, 2022**

(54) **MEASURING INSTRUMENTS, APPARATUS AND DEVICES**

(71) Applicant: **Binder GmbH**, Tuttlingen (DE)

(72) Inventor: **Michael Tinius**, Elchingen (DE)

(73) Assignee: **Binder GmbH**, Tuttlingen (DE)

(**) Term: **15 Years**

(21) Appl. No.: **29/726,966**

(22) Filed: **Mar. 6, 2020**

Related U.S. Application Data

(62) Division of application No. 29/666,659, filed on Oct. 15, 2018, now Pat. No. Des. 883,107.
